POWDER DISTRIBUTING APPARATUS

Clarence J. Davies, Detroit, Mich., assignor to
 National Automotive Fibres, Inc., Detroit,
 Mich., a corporation of Delaware

Application April 15, 1940, Serial No. 329,769

2 Claims. (Cl. 91—18)

The present invention relates to powder distributing apparatus and more particularly to apparatus for forming a fibrous batt having powder uniformly distributed therethrough.

In my prior copending application Serial No. 323,430, entitled "Sheet material," filed March 11, 1940, I have disclosed the method of making as a new product of manufacture a fibrous material having a binder uniformly distributed therethrough, in which the binder is substantially concentrated near the surface, and the surface is smoothed by an operation set forth in detail in said earlier application.

The present apparatus comprises means for building up or forming a continuous fibrous batt and for distributing powder uniformly therethrough. The powder, as set forth in my prior application referred to above, is preferably a resin or similar material adapted upon heating to soften and to reset upon cooling.

Briefly described, according to the present invention, the continuous batt of fibrous material is built up by means of a Garnett in which a thin film of cotton is generated by means of a picker and is fed by suitable conveyors to a cross lapper. The cross lapper is adapted to deposit the film of fibrous material on an advancing conveyor and it is reciprocated back and forth across the conveyor so that the film of fibrous material is built up into a plurality of laterally overlapping folds, thus forming a batt of the desired thickness. Obviously, of course, a plurality of Garnetts may be employed in conjunction with a single floor apron, but in the present application I have illustrated and described a single Garnett. If more than one is used, the apparatus disclosed herein is merely duplicated.

Means are provided for depositing powdered material on the thin film of fibrous material as it is generated, or shortly thereafter. The film of fibrous material at this time is very thin and the powdered material seeps down into the fibrous material to some extent. However, in the completed continuous batt it is found that the powdered material has a tendency to be present in strata so that the fibrous batt comprises alternate layers of fibrous material and layers of powder.

In the product previously referred to it is quite important that the distribution of powder through the fibrous material shall be substantially uniform. Accordingly I have devised the present apparatus for insuring uniformity of distribution of powdered material. This apparatus takes the form of means for progressively com-

pressing the batt in such a way as to force entrapped air longitudinally therethrough. The movement of the entrapped air longitudinally of the batt is effective to distribute the powdered material uniformly therethrough, and the mechanical compression which accompanies the process is also instrumental in rendering uniform the distribution of powder.

The apparatus for performing the aforesaid functions comprises essentially a lower supporting conveyor, preferably inclined substantially from the horizontal, over which the stratified fibrous batt is advanced. A second conveyor is provided overlying the fibrous batt. This conveyor is in the form of a flexible belt adapted to contact the upper surface of the fibrous material and to move synchronously therewith. Means are provided adjacent the portion of the upper flexible belt which contacts the upper surface of the fibrous material, and this means is adapted to compress the fibrous material a substantial amount progressively, and preferably the progression of compression moves in a direction opposite to the advance of the fibrous material. This last means may conveniently take the form of one or a plurality of rollers, and means are provided for moving the rollers in pressure contact with the upper flexible belt opposite to the direction of travel of the fibrous material at a rate substantially greater than the rate of advance of fibrous material. This has the effect of forcing entrapped air longitudinally through the fibrous batt and rendering uniform the distribution of powdered material as aforesaid.

With the foregoing general remarks in view, it is an object of the present invention to provide means for generating a fibrous batt and for providing uniform distribution of a powdered material therethrough.

It is a further object of the present invention to provide apparatus for rendering uniform a non-uniform distribution of powdered material throughout a fibrous batt.

It is a further object of the present invention to provide apparatus for rendering uniform a non-uniform distribution of powdered material in a fibrous batt which comprises means for progressively compressing the fibrous batt in a manner to displace entrapped air longitudinally therethrough.

It is a further object of the present invention to provide apparatus of the character described characterized by the use of a flexible impervious sheet material adapted to overlie a fibrous batt in combination with means for progressively

moving the sheet material in a manner to compress a fibrous batt.

Other objects of the invention will be apparent as the description proceeds, and when taken in conjunction with the accompanying drawings wherein:

Figure 1 is a diagrammatic view of a Garnett equipped with means for distributing powder on a film of generated fibrous material;

Figure 2 is a side elevation of the apparatus for rendering uniform the distribution of powder;

Figure 3 is a fragmentary top view of the rear of the machine shown in Figure 2 taken in the direction of the arrows 3—3 of Figure 2;

Figure 4 is a fragmentary top plan view of the front side of the apparatus shown in Figure 2 taken in the direction of the arrows 4—4 of Figure 2; and

Figure 5 is a section on the line 5—5 of Figure 2.

Referring first to Figure 1, I have illustrated a Garnett machine of the type adapted to generate a batt of fibrous material indicated at 10 which comprises a frame having uprights 11 and 12 and cross members 13. Intermediate the uprights 11 and 12 is a conveyor or floor apron 14 mounted on rollers 15 carried by the uprights 11 and 12. A cross lapper carriage 16 is mounted for reciprocation back and forth across the cross pieces 13, suitable rollers 17 being provided. The carriage 16 has a depending portion 18 which in turn carries a pair of rollers 19 and 20, and a pair of upper rollers 21 and 22.

A very thin film of fibrous material is generated from a roll 23 and is picked from the roll by a picker 24, whence it is fed across a feed roll 25 on to a conveyor 26 carried by rolls 27 and 28. After the thin film of fibrous material has been removed from the roll 23, powdered material is distributed thereon by suitable means, and I have indicated diagrammatically at 29 one such means. This may take the form of a receptacle for powdered material provided with a perforated bottom in combination with means for continuously causing powdered material to be sifted downwardly through the perforations. The details of the sifting device form no part of the present invention and many suitable devices for this purpose are available.

A second conveyor 30 mounted between rolls 31 and 32 is adapted to receive the film of fibrous material indicated at 33 and to advance the same toward the cross lapper carriage. A pair of conveyors 34 and 35 are provided extending over upper rolls 36 and 37, respectively, and are arranged to advance the thin film of fibrous material downwardly therebetween. The lower ends of the conveyors 34 and 35 are carried by the rolls 22 and 21 previously referred to.

Suitable mechanism is provided for causing the carriage 22 to reciprocate back and forth across the floor apron 14, and this means is diagrammatically indicated in Figure 1. A drive pulley 40 is provided having a belt 41 and a cross belt 42 adapted to reversely drive a shaft 43 having pulleys 44 thereon. A shifting fork is indicated at 45 and is adapted to be actuated responsive to reciprocation of the carriage 16. Means for causing shifting of the shifting fork 45 includes a rod 46 having stops 47 and 48 thereon. When the carriage 16 engages one of the stops it shifts the rod 46 which is connected by suitable linkage 49 with the shifter fork 45.

The floor apron is advanced continuously at a slow rate relative to the reciprocation of the car-

riage 16 so that the thin fibrous web is folded into a plurality of transversely overlapping folds. Obviously the thickness of the completed batt 10 depends upon the rate of advance of the floor apron 14.

Referring now to Figure 2, I have illustrated the side elevation of the apparatus for rendering uniform the non-uniform distribution of the powdered material in the fibrous batt 10. This means comprises a frame having uprights 60 and 61 which are herein illustrated as being formed of angle iron. Spanning the uprights 60 and 61, and at a substantial angle to the horizontal, are frame elements 62. Carried on the inclined frame element 62 are rollers 63 mounted in suitable brackets 64, one of which is illustrated as being adjustable by adjusting means 65 for the purpose of varying the tension in a conveyor belt 66. Also carried by the cross piece 62 is a flat supporting member 67 over the upper surface of which the conveyor belt 66 moves. The support 67 is carried from the inclined frame member 62 by suitable supporting means 68, which may be angle irons or the like.

The lower run of the conveyor belt 66 advances between plates 70 and 71 suitably supported from the inclined frame member 62. As indicated in Figure 2, the plates 70 and 71 have curved ends 72 and 73, respectively, curved away from the conveyor belt.

The balance of the structure is adjustably carried from the frame structure thus far described and comprises longitudinal frame members 80 connected by suitable cross members in conjunction with relatively long frame members 81 extending substantially perpendicular to the frame members 80. Brace members 82 interconnect members 80 and 81 as seen in Figure 2. The structure comprising frame members 80, 81 and 82 is supported from the lower frame by means which will now be described. Brackets 85 are bolted or otherwise secured to the inclined frame members 62 and are provided with recesses 86. Within the recesses are rotatably positioned threaded studs 87 having keyed or otherwise secured thereto a nut-like member 88. The member 88 is adapted to be gripped by a wrench or suitable tool and rotated thereby, rotating the threaded studs 87. Secured on the underside of frame members 80 are depending internally threaded projections 90 in which the studs 87 are threaded, suitable lock nuts 91 being provided. In order to adjust the upper frame toward the lower frame, it is necessary only to loosen the lock nut 91 and then to rotate the member 88, thus rotating the threaded stud and effecting adjustment of the upper frame relative to the lower. The stud 87 is mounted for free rotation in the bracket 85 as previously described.

Carried by the upper frame are rollers 100, 101 and 102. The rollers 100 and 102, as indicated, are secured directly to the inclined frame members 80, whereas the roller 101 is carried by an adjustable support 103 on the frame member 81. These rollers have a flexible conveyor belt 104 carried thereby, and in order to tighten the belt 104, adjusting means indicated generally at 105 are provided for the adjustable support 103. Intermediate the rollers 101 and 102 I provide a movable frame portion 110 which is retained in adjusted position by means of a lock-nut 111 associated with an elongated slot 112 carried by a supporting bracket 113. Frame members 110 have secured thereto a flat plate 114 having a curved edge 115 and an oppositely dis-

posed plate 116 having a curved edge 117. The conveyor belt 104 is adapted to pass between the plates 116 and 114.

The frame member 82 has secured thereto a bracket 120 having a sprocket 121 mounted thereon and a drive chain 122 passes over the sprocket 121. I have indicated a second sprocket 123 which is associated with the main frame and may have suitable driving means connected therewith. The roller 63 is mounted on a shaft 124 which has a driving sprocket 125 keyed or otherwise secured thereto. The roller 100 previously referred to is mounted on a shaft 126 and a sprocket 127 is keyed or otherwise secured to this shaft. The chain 122 passes around sprockets 121, 123, 125 and 127. The sprockets 125 and 127 and the rollers 100 and 63 are the same size so that the conveyor belts 66 and 104 are driven at the same speed. Also due to the relationship of the chain 122 to the sprockets 125 and 127, the lower run of the belt 104 moves in the same direction and synchronously with the upper run of the conveyor belt 66.

Mounted on the upper frame and carried by the frame members 80 are a pair of brackets 130 carrying sprockets 131. A chain 132 extends between the sprockets 131 and mounted on the chain are extending supporting members 133 adapted to support a roller 134 therebetween. In Figure 2 I have illustrated two such rollers, although one or any number may be provided. The rollers 134 are adapted to extend completely across the conveyor for a purpose which will subsequently be described.

Carried by the upper frame and mounted on a frame member 81 is an independent driving motor 140. The rotor of this motor has keyed or otherwise secured thereto a pinion 141 which engages a gear 142 carried by a shaft 143 which is carried by a bracket 144 formed on a supporting plate 145, as best seen in Figure 4. Also carried by the shaft 143 is a smaller sprocket 146 adapted to drive a chain 147 which in turn drives a sprocket 148 carried by a shaft 149, which in turn supports the sprocket 131 previously referred to. The direction of rotation of the chain 132 is such as to cause the rollers 134 to move in the direction of the arrow 150. Preferably the chain 132 is driven at a relatively high speed, and by way of example excellent results have been obtained when this speed has been approximately 150 feet a minute. It will be observed that the roller 134 is adapted to contact the upper surface of the belt 104 and to move the same in a manner to compress the fibrous material 10 which is being advanced by the conveyor belt 66. Furthermore, the flat support 67 previously defined supports the conveyor belt 66, to render this compression effective. As the fibrous material 10 is advanced upwardly along the inclined support 67 the roller or rollers 134 move relatively rapidly down the

incline in a manner to cause rapid displacement of entrapped air along the batt. Furthermore the mechanical displacement of the fibrous material by the roller or rollers 134 is also effective to assist in rendering uniform the distribution of powdered material. Since as above stated the operation is effective to rapidly displace entrapped air along the batt, the belts 66 and 104 are substantially impervious to air.

10 Referring now particularly to Figure 5, means are provided for holding the chain in a straight line intermediate the sprockets 131. This means comprises a bar 160 carried by a bracket 161 secured to cross pieces 162 which are supported from the inclined frame member 80 by means of blocks 164 positioned intermediate frame members 80 and cross pieces 162. In Figure 5 I have indicated a bolt 165 as securing the cross piece 162 to the frame member 80 through the medium of the blocks 164.

15 By this arrangement the rollers 134 are caused to move in a straight line while in contact with the upper belt 104 and to compress the fibrous material 10 therebeneath uniformly.

20 The foregoing apparatus is adapted to fabricate a continuous batt of fibrous material having a powdered material substantially uniformly distributed therethrough. It may be mentioned that the powdered material is preferably a thermoplastic resin, and the further processing of the material comprises the steps of heating the thermoplastic powder to soften the same and then to cause the same to set, thereby binding the fibers of the batt together.

25 30 While I have illustrated a single embodiment of the machine, it will be understood that this has been done solely to enable those skilled in the art to practice the invention the scope of which is indicated by the appended claims.

35 40 What I claim as my invention is:

1. A substantially impervious support for a batt of fibrous material, a flexible, substantially impervious cover adapted to rest on fibrous material carried by said support, and means engaging said cover and relatively movable parallel thereto for progressively compressing said fibrous material between said cover and support in a manner to displace entrapped air along said fibrous material.
